(57) **CLAIM**

The ornamental design for hand bottle cover as shown and described.

DESCRIPTION

FIG. 1 is an upper-left perspective of a hand bottle cover; FIG. 2 is a lower-left, front perspective view of the hand bottle cover of FIG. 1;

FIG. 3 is a left side elevation view of the hand bottle cover of FIG. 1;

FIG. 4 is a right side elevation view of the hand bottle cover of FIG. 1;

FIG. 5 is a top plan view of the hand bottle cover of FIG. 1; FIG. 6 is a bottom plan view of the hand bottle cover of FIG. 1;

FIG. 7 is a front elevation view of the hand bottle cover of FIG. 1; and,

FIG. 8 is a rear elevation view of the hand bottle cover of FIG. 1.

The broken lines in the drawings are for purposes of illustrating the environment in which the hand bottle cover is used and form no part of the claimed design.
